A. E. SNOW.

CLOTHES PRESSING APPARATUS.

APPLICATION FILED JUNE 19, 1918.

Patented Nov. 15, 1921.

Inventor
Arthur E. Snow
By J. G. Washington, Atty.

UNITED STATES PATENT OFFICE.

ARTHUR E. SNOW, OF ERIE, PENNSYLVANIA, ASSIGNOR TO THE AMERICAN LAUNDRY MACHINERY COMPANY, OF NORWOOD, OHIO, A CORPORATION OF OHIO.

CLOTHES-PRESSING APPARATUS.

1,397,300.

Specification of Letters Patent. Patented Nov. 15, 1921.

Application filed June 19, 1918. Serial No. 240,866.

To all whom it may concern:

Be it known that I, ARTHUR E. SNOW, a citizen of the United States, residing at Erie, in the county of Erie and State of Pennsylvania, have invented certain new and useful Improvements in Clothes-Pressing Apparatus; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to garment pressing apparatus, and has for its object the construction and combination of a puff-iron, with which the shoulders and collars of garments may be steamed and formed into proper shape, with the upper steam heated oscillating buck of a clothes pressing apparatus in such a manner that it will not be in the way of the operator using the other features of the machine, when not in use.

20 These objects I accomplish by constructing a puff-iron of suitable shape to fit the inside of the shoulders or collar of a coat, and securing it to the oscillating steam heated press-buck of a clothes pressing apparatus in such a manner that it will be practically above the front end of the buck, and move up and down in unison therewith, and receive its steam supply from the buck when it is in its lowermost position.

25 These and other features of my invention will appear hereinafter and are illustrated in the accompanying drawings in which:

30 Figure 1, is a side elevation of a garment pressing apparatus with my improved puff iron mounted thereon.

35 Fig. 2, is a transverse section of my improved puff iron on the line $x-x$ in Fig. 3.

40 Fig. 3, is a longitudinal section of the same on the line y in Fig. 2.

45 In these drawings A indicates an upright standard or support; B indicates a work table supported on said standard; B' indicates an ironing board or press buck also supported on said standard; C indicates an oscillatory arm or lever pivoted on the upper end of the standard A, to which is secured a hollow press buck C', to which steam may be supplied through the pipes

$c-c'$ from any suitable source of supply 55 (not shown) for the purpose of heating the press buck C'. The press buck C' can be raised and lowered as indicated by broken lines in Fig. 1, as may be desired, by means of the handle D thereon.

50 Secured to the upper part of the front end of the hollow press buck C', and connected to the hollow press buck C', there is a hollow rounded puff iron F, preferably supported by a pipe E, through which it receives its steam supply from the press buck C' when the press buck C' is closed down upon the lower buck B', and is then in convenient position to be used and at the same time does not in any wise interfere with the 60 use of press bucks C' and B' in the usual and ordinary manner; and when the press buck C' is raised, the puff iron is raised up out of the way, in unison therewith, as indicated by broken lines in Fig. 1.

55 In constructing my improved puff-iron F, I make a lower section f (see Figs. 2 and 3) with a flat upper wall f', said flat upper wall being secured to the lower semi-cylindrical or oval wall thereof by means of an 65 integral stud f'' having a longitudinal opening therethrough to receive a screw f''. The upper flat wall f is provided with a very small opening f''' to permit steam to flow from the interior of the section f. Upon the 70 upper flat surface f' of the section f, I place an upper semi-cylindrical section G, having a downwardly projecting stud G', having a screw threaded opening therein to receive the upper end of the screw f'' by means of 75 80 which the section G is held in place so as to cover the flat upper surface of the lower section f of the puff-iron.

85 The upper section G is provided with small perforations g through the curved wall thereof. Steam is supplied to the lower section to heat the iron, and a small portion thereof flows through the restricted opening f''' into the upper section from which it escapes through the perforated wall thereof 90 in a fine vapor. When it is desired to steam shoulders and collars of garments, the puff-iron is lowered and the fabric to be steamed is placed over the iron and the steam or vapor from the perforations will penetrate 95 therethrough, and the garment can be moved along over the iron as may be desired, and when the operator has finished using the 100 105

puff-iron and releases pressure thereon, or on the handle D, the counterweighted lever C will raise it upward out of the way.

Having thus fully shown and described my invention so as to enable others to utilize the same, what I claim as new and desire to secure by Letters-Patent is:—

1. In a combined press and puff iron structure, a press including a hollow member provided with steam supply means, a puff iron mounted upon and arranged above said member, and steam connection between said puff iron and said member.

2. In a combined press and puff iron structure, a press including a head having steam supply means, a steam pipe extending upward from said head, and a puff iron mounted upon and communicating with said steam pipe and comprising a hollow heating member and an upper perforated member, there being communication between the upper and lower members of the puff iron.

3. A puff iron, comprising upper and lower members, the lower member having an upper wall provided with a restricted through opening and a lower curved wall, tie means connecting said upper and lower walls, a securing device passing through said tie means and extending above said upper wall, the upper member being provided with perforations through the wall thereof and adapted to seat upon the lower member, a stud on said upper member adapted for connection to said securing device for securing said members together, and means for supplying steam to the lower member.

4. A puff iron, comprising a hollow cham-

ber lower member having a horizontal upper wall provided with an opening, a lower wall 40 for said member, a steam supply conduit communicating with the chamber in said member, an inverted dish shaped upper member having the edge of its wall seated upon the outer portion of the upper wall 45 of the lower member, and means for securing said members together.

5. A puff iron, comprising a hollow chamber lower member having a horizontal upper wall provided with an opening, a lower 50 wall for said member, a steam supply conduit communicating with the chamber in said member, an inverted dish shaped upper member having the edge of its wall seated upon the outer portion of the upper wall 55 of the lower member, and means accessible from beneath the lower member and passing through the same and engaging the upper member for securing said members together.

6. A puff iron, comprising a hollow chamber lower member having a horizontal upper wall provided with an opening, a lower wall for said member, a steam supply conduit 65 communicating with the chamber in said member, an inverted dish shaped upper member having the edge of its wall seated upon the outer portion of the upper wall of the lower member, and a single device located at approximately the center of the 70 lower member and passing through the same and engaging the upper member for detachably securing said members together.

In testimony whereof I affix my signature.

ARTHUR E. SNOW.
